UNITED STATES PATENT OFFICE

2,613,507

OPEN TOP FROZEN FOOD REFRIGERATOR

Richard E. Pabst, San Antonio, Tex., assignor to
 Ed Friedrich, Inc., San Antonio, Tex., a corpora-
 tion of Texas

Application January 30, 1950, Serial No. 141,268

3 Claims. (Cl. 62—89.5)

1

My invention has for its objects to provide:

1. An open top refrigerated display case having a display compartment and a storage compartment with individual and cooling or refrigerating coils, the air movements in both chambers being under the influence of a single blower.

2. A frozen food case having a display compartment, a storage compartment, an air-pressure duct common to both compartments, an air-suction duct also common to both compartments, and a single blower for establishing air circulations in the two compartments between the pressure duct and the suction duct.

3. A frozen food case in which the display and storage compartments are separated by a horizontal partition which forms the bottom of a common suction duct, the top of which is formed by the food shelf of the display compartment.

Other objects will in part be obvious and in part will be pointed out hereinafter.

To the attainment of the aforesaid objects and ends, invention still further resides in the novel details of construction, combination and arrangement of parts, all of which will be first fully described in the following detailed description, and then be particularly pointed out in the appended claims, reference being had to the accompanying drawings, in which:

Fig. 1 is a horizontal section on the line 1—1 of Fig. 2, the food shelf of the display compartment being omitted.

Fig. 2 is a cross section on the line 2—2 of Fig. 1, with the food shelf in place.

Fig. 3 is a detail vertical section on the line 3—3 of Fig. 2.

In the drawings, in which like numerals and letters of reference indicate like parts in all the figures, 1 is the case, which includes a back wall 1^a, a front wall 1^b and a base 1^c. The interior exposed surfaces are metal sheathed, as at 2, and a triple glass window 3 is provided on the front wall 1^b.

The case has two compartments, the upper or display compartment being indicated by DC, while the lower or storage compartment is indicated by SC. The two compartments are separated by a horizontal partition 7, which has air holes or passages 7^a adjacent the front wall of the case and which has a stepped-up portion 7^s adjacent the rear of the cabinet.

6 is a longitudinal vertical partition running from side to side of the cabinet and spaced from the back wall so as to leave a space constituting a common high-air-pressure duct, indicated by CPD. The wall 6 also has a stepped-up portion 6^a, an upwardly-rearwardly inclined portion 6^c

2

and a vertical upper-end portion 6^d. One of the longitudinal edges of the partition 7 is supported by the stepped-up portion 6^a of the vertical partition 6.

Immediately below the partition portion 7^s and within the common pressure duct CPD, is a lower refrigeration coil unit 12 the rear of which is covered by a plate 13 secured to the wall portion 6^a in order that the chilled air passing from the coil unit 12 will be forced to pass through the apertures 6^e. Above the level of the unit 12 and bridging the space between the rear wall of the case and the partition portion 6^a is another refrigerating coil unit 14, the air chilled by it passing in part through a row of openings 6^b in the partition portion 6^a and the remainder passing up the partition portion 6^c, 6^d and over the latter into the display compartment or chamber DC, a concave baffle 15 being provided to cooperate with the partition portion 6^c in directing the air-flow over the goods in the compartment DC toward the front of the case.

Adjacent the front wall of the cabinet, but spaced from the same by a stepped supporting strip 17, is a glass baffle holder 18 which supports a glass baffle 18^a. The strip 17 between the wall 1^b and the baffle holder 18 has a row of return-air-holes 17^a that communicate with the common suction or low pressure duct CSD formed between the partition 7 and a display shelf 19 that is supported by the strip 17 and the partition portion 7^s. The common suction duct CSD has a central opening 7^b in the partition 7 for passing air into the blower box 8 that is located adjacent the wall 6 and contains a blower unit 9 whose discharge end 10 delivers air under pressure, through an opening 6^c in the wall 6, into the common pressure duct CPD. Air enters the box 8 only through the top, that portion of which that lies beneath the partition portion 7^s being closed by a U-shaped baffle 11. A suitable blower unit 9 is located in the box 8 and takes the air from the box and forces it into the duct CPD, while at the same time creating a suction to draw air into the box.

45 Access to the chamber SC is had through a door-opening 4 that is normally closed by a door 5.

The improvements made by me enable the displayed merchandise in the chamber DC to be cooled by cold air passed over the top and by conduction through the metal shelf 19 of the return cool air in duct CSD, while the merchandise in the chamber SC will be kept at a low temperature by the air chilled by the coil unit 12 and, as the air from the chamber SC is re-

turned at the front adjacent the door 5, periodic opening of the door—when it is desired to remove or insert merchandise from or into the storage chamber—will not effect a substantial temperature increase in the chamber SC.

The advantages of my construction of refrigerator over those in common use will be readily apparent to those skilled in the art.

What I claim is:

1. In an open top refrigerated display case comprising front, back and side walls, a vertical partition extending between the said side walls and spaced from said back wall for forming an air duct, a horizontal partition dividing the display case to provide a display chamber and a storage chamber, a shelf supported in spaced relation to said horizontal partition for forming a suction duct therebetween, said horizontal partition having an opening therein for admitting air from said storage chamber to said suction duct, a baffle located in spaced relation to said front wall in said display chamber and forming with said front wall a passage for air from said display chamber to said suction duct, means forming an air passage between said suction duct and said air duct, said vertical partition being provided with an opening for forming communication between said storage chamber and said air duct, and provided with a second opening therein located above said shelf for forming communication between said air duct and said display chamber, cooling means located in said air duct adjacent said openings in said vertical partition for delivering cold air to said storage and display chambers, and a blower located in said air passage means connecting said suction duct and said air duct for conducting air from said display and storage chamber through said suction duct to said air duct.

2. In an open top refrigerated display case, comprising front, back and side walls, a vertical partition extending between the said side walls and spaced from said back wall for forming an air duct, a horizontal partition dividing the display case to provide a display chamber and a storage chamber, a shelf supported in spaced relation to said horizontal partition for forming a suction duct therebetween, said horizontal partition having an opening therein for admitting air from said storage chamber to said suction duct, a baffle located in spaced relation to said front wall in said display chamber and forming with said front wall a passage for air from said display chamber to said suction duct, a blower box located in said storage chamber and connected to said horizontal partition and vertical partition for forming an air passage between said suction duct and said air duct, a blower in said blower box for conducting air from said display

and storage chambers through said suction duct to said air duct, said vertical partition provided with openings for establishing communication between said air duct and said storage and display chambers, respectively, and cooling means located in said air duct for cooling the air in said air duct prior to delivery thereof to said storage and display chambers.

3. In an open top refrigerated display case, comprising front, back and side walls, a vertical partition extending between said side walls and spaced from said back wall for forming an air duct, a horizontal partition supported by said front wall and said vertical partition dividing the display case to provide a display chamber and a storage chamber, a shelf supported by said front wall and said horizontal partition in spaced relation to said horizontal partition for forming a suction duct therebetween, said horizontal partition having an opening therein for admitting air from said storage chamber to said suction duct, a baffle located in spaced relation to said front wall in said display chamber and forming with said front wall a passage for air from said display chamber to said suction duct, means forming an air passage between said suction duct and said air duct, said vertical partition provided with an opening for forming communication between said storage chamber and said air duct, and provided with a second opening therein located above said shelf for forming communication between said air duct and said display chamber, cooling means located in said air duct adjacent the opening in said vertical partition for the delivery of cold air to said storage chamber, said vertical partition provided with a second opening therein located above said shelf for forming communication between said air duct and said display chamber, a second cooling coil located in said air duct adjacent said second opening in said vertical partition for delivering cold air to said display chamber, means for directing air from said air duct to said display chamber, and a blower located in said air passage means between said suction duct and said air duct for conducting air from said display and storage chamber through said suction duct to said air duct.
